UNITED STATES PATENT OFFICE.

PAUL GAETH, OF CLEVELAND, OHIO.

PROCESS OF GRINDING PISTON-RINGS.

No. 831,151.

Specification of Letters Patent.

Patented Sept. 18, 1906.

Application filed November 14, 1905. Serial No. 287,292.

To all whom it may concern:

Be it known that I, PAUL GAETH, a citizen of the United States, residing at Cleveland, in the county of Cuyahoga and State of Ohio, 5 have invented new and useful Improvements in Processes of Grinding Piston-Rings, of which the following is a specification.

This invention is a process of grinding and fitting pistons and piston packing-rings.

10 In the existing state of the industry the piston and rings are ground separately, the rings being ground before they are placed in position on the piston. This is defective, because the best fit is not obtained and for 15 other reasons. By means of the present invention the piston and rings are ground at the same time and while the latter are in position. Since the rings yield under pressure, means must be provided to hold them out 20 flush or in proper position during the grinding operation. This is done by running in some readily-fusible substance under or behind the rings, which when it solidifies holds the rings in place and prevents them from 25 yielding inwardly under the pressure of the grinding implement. Said substance is afterward melted out, and the rings are left in place at a true and correct fit.

The invention is illustrated in the accompanying drawings, Figure 1 being a sectional elevation showing the manner of locating and centering the rings on the piston. Fig. 2 is a section of the piston, showing the rings in position and the means for introducing the fusible substance behind the same.

Primarily the piston and rings are turned to the size wanted plus the allowance for grinding. The rings, which are indicated at 6, are then slipped in position in their grooves 40 in the piston, so that all the laps 7 come in a straight line down the side of the piston. The sleeve 8 is then slipped over the piston, thus centering the rings in place on the piston. Holes are then drilled lengthwise 45 through the walls of the piston 9 and through the ends of the rings adjacent to the lap to receive wires 10, which thus hold the rings and prevent them from turning or spreading apart during the grinding operation. After 50 this is done the piston, which, as shown, is of the trunk type, is turned upside down and filled with a readily-fusible substance, such as wax, and this is heated, causing the substance to run through the holes 11 into the 55 spaces 12 in the grooves under the rings.

The holes 11 are previously drilled before the rings are put in place. The piston is then cooled and the fusible substance solidified. Now the piston and its rings are ready for grinding and can be ground and polished by 60 any of the approved machines or means for that purpose. The rings are held against rotation and also against yielding inwardly and are so acted upon by the grinding instruments the same as the piston and are ground 65 to the true surface and accurate diameter desired. After the piston and rings are ground to size and finish the piston is reheated and the readily-fusible substance is run out. The wires 10 are then withdrawn and the holes in 70 which they were contained are plugged up. Pins are also put into the holes 11.

The process is not confined to a piston or its rings nor to the particular type of piston shown for the purpose of illustration, but 75 may be applied to any analogous device where a yielding packing-ring or surface is to be ground or polished in connection with a relatively rigid part or surface. The method described saves the labor of two separate operations upon the respective parts and also insures a better fit and more correct size.

I claim:

1. The method of grinding simultaneously a relatively rigid part and a relatively yielding part carried thereby, consisting in supporting the latter in unyielding position upon the former during the grinding operation.

2. The method of truing and grinding the surfaces of two adjacent parts of the same 90 structure, one of said parts being relatively rigid and the other yielding, consisting in supporting the latter in unyielding position upon the former by means of a readily-fusible substance during the truing and grinding operation.

3. The method of grinding packing-rings, consisting in placing the same in the grooves in the member in which they are to remain, introducing a readily-fusible substance in the 100 grooves under the rings, applying the member and rings to a grinding instrument when said substance has hardened, and finally melting out said substance.

4. The method of simultaneously grinding 105 a piston and its packing-rings, consisting in centering said rings in their places on the piston, and supporting said rings unyieldingly in such position during the grinding operation.

5. The method of simultaneously grinding a piston and its packing-rings, consisting in centering and fixing said rings in their places on the piston with their surfaces flush with the surface of the piston, and holding said rings in said position unyieldingly during the grinding operation.

In testimony whereof I have signed my name to this specification in the presence of two subscribing witnesses.

PAUL GAETH.
